DESIGN FOR A KNIFE HOLDER

Gaylord R. Hove, New Hampton, Iowa

Application January 25, 1945, Serial No. 117,604

Term of patent 7 years

(Cl. D44—29)

To all whom it may concern:

Be it known that I, Gaylord R. Hove, a citizen of the United States, residing at New Hampton, in the county of Chichasaw and State of Iowa, have invented a new, original, and ornamental Design for Knife Holders, of which the following is a specification, reference being had to the accompanying drawing, forming part thereof.

The figure is a perspective view of a knife holder, showing my new design.

I claim:

The ornamental design for a knife holder, substantially as shown.

GAYLORD R. HOVE.
